UNITED STATES PATENT OFFICE

ALBERT F. WEISS, OF UNIVERSITY CITY, MISSOURI, ASSIGNOR, BY MESNE ASSIGNMENTS, OF ONE-HALF TO ALBERT F. WEISS AND ONE-HALF TO ELMER V. KLINE, BOTH OF UNIVERSITY CITY, MISSOURI

DESIGN FOR A SAFETY RAZOR BLADE SHARPENER

Application filed August 1, 1931. Serial No. 40,752. Term of patent 14 years.

To all whom it may concern:

Be it known that I, ALBERT F. WEISS, a citizen of the United States, residing at University City, St. Louis County, Missouri, have invented a new, original, and ornamental Design for Safety Razor Blade Sharpener, of which the following is a specification, reference being had to the accompanying drawings forming part thereof.

Fig. 1 is a perspective view of the safety razor blade sharpener showing my new design.

Fig. 2 is a perspective view from the opposite end of the safety razor blade sharpener.

I claim:

The ornamental design for a safety razor blade sharpener, substantially as shown.

ALBERT F. WEISS.
